UNITED STATES PATENT OFFICE.

HERBERT G. BEEDE, OF PAWTUCKET, RHODE ISLAND.

DRIVE MECHANISM FOR TWISTING AND SPINNING FRAMES.

Application filed February 19, 1923. Serial No. 619,793.

To all whom it may concern:

Be it known that I, HERBERT G. BEEDE, a citizen of the United States of America, and resident of Pawtucket, in the county of Providence and State of Rhode Island, have invented new and useful Improvements in Drive Mechanism for Twisting and Spinning Frames, of which the following is a specification.

This invention concerns twisting or spinning frames and relates more particularly to improved spindle driving means therefor.

The spindle whisks are usually driven by means of endless bands or belts, but as it is impossible to pass an endless band about the driving drum or pulley due to the presence of the shaft upon which the latter is mounted, it is usual to make the bands from straight strips, splicing the ends together after the band has been passed about the drive shaft. This splicing of the bands consumes considerable time during which the spindle must remain idle, and at best, such a spliced band is not as satisfactory as an integrally continuous or jointless band would be.

The principal object of the present invention is to provide a drive mechanism for the spindles of twisting and spinning frames of such character as to permit the employment of endless woven or other integrally continuous bands for driving the spindles.

In the accompanying drawings a preferred arrangement of parts, together with certain modifications thereof, is shown as illustrative of the various specific arrangements in which the invention may find embodiment.

Fig. 1 is a fragmentary plan view of a spinning or twisting frame of usual construction having the present invention applied thereto;

Fig. 2 is an elevation partly in section of the parts shown in Fig. 1;

Fig. 3 comprises a diagrammatic plan view and a diagrammatic end elevation respectively of a modified form of apparatus; and

Fig. 4 comprises a similar diagrammatic plan view and end elevation of a further modification.

Referring to Figs. 1 and 2, the longitudinal frame members of the machine are indicated at 1—2 respectively. A series of transverse supporting members such as 3 extend between the frame members 1—2 and

these supporting members 3 serve to support journal brackets for a driving shaft 4. This shaft is provided at one end of the machine with a pulley 5 for a driving belt and with a series of spindle driving pulleys 6. A shaft 7 is mounted in suitably supported bearings and on this shaft a series of loose guide pulleys 9 are mounted, these pulleys being arranged in the vertical plane of the drive pulleys 6. Upon suitable supporting means 10 bell crank levers 11 are pivotally supported. One arm of each lever extends upwardly and is provided with a stub shaft 12 upon which a tension pulley such as 13 is mounted. The tension pulleys 13 are arranged in the planes of the corresponding drive pulleys 6. The bell crank levers 11 are also furnished with lateral arms 14 to which weights 15 are secured, the arrangement being such that the tension pulleys 13 tend to approach the respective drive pulleys. The side frame members 1 and 2 are provided with series of spindles such as 16, 17 respectively, each spindle being furnished with the usual whirl for driving it. An endless and jointless band such as may be formed by a weaving or other textile process partially encircles spindles at each side of the machine. As indicated in Fig. 1 the band may engage a single spindle at each side of the machine, or two or more spindles at each side, as may be desired. This band or belt comprises an idle run 20, and a driving run which passes beneath the pulley 9 as indicated at 21, over the drive pulley 6 as at 22, and beneath the tension pulley 13 as shown at 23. Similar bands or belts partially encircle the next adjacent spindles or groups of spindles and are caused to engage the proper drive pulley 6 by passing beneath the corresponding guide pulley 9 and tension pulley 13.

In operation, the weight 15 serves to press the tension pulley into contact with the driving run of the band, thus maintaining driving engagement of the band with the driving pulley. It will be observed that this band does not completely enclose or encircle either the shaft 7 or the driving shaft 4 so that it is possible to apply and remove the band without splicing or severing the same. A continuous and jointless band may thus be employed so that the operation of applying the band to the machine is greatly simplified and the time consumed for the operation is decreased. Fur-

thermore, the tension pulley exerts a constant pressure upon the band which keeps it in proper operative condition so that it is unnecessary to take up the band manu-
5 ally and the efficiency of the band is continuously maintained at its highest point.

In Fig. 3 a slight modification is indicated in which spindles 30, 31 are shown at opposite sides of the machine, the driving pulley 13 being arranged intermediate such spindles, while a guide pulley 33 is mounted to turn about a fixed axis in the plane of the driving pulley. A movable tension pulley 34 is also arranged in the same plane, 10 15 being carried upon a sliding bar or frame 35 mounted in a support 36. This tension pulley is normally urged toward the drive pulley 42 by means of a bell crank lever comprising the vertical arm 36 which engages 20 the outer end of the slide member 35, this lever being pivoted at the point 38. The opposite arm 39 of the lever is furnished with a weight whose tendency is to move the pulley 34 toward the pulley 32. A 25 driving band 40 encircles the spindles 30, 31, passing over the guide pulley 33, beneath the drive pulley 32, and over the tension pulley 34. This belt or band 40 may also be of continuous type without joint and 30 capable of application to the spindles and drive pulley in a manner similar to that previously described.

In Fig. 4 spindles 40, 41 are shown as arranged at opposite sides of drive pulley 42. In this case the guide pulley 43 turns about a fixed axis below the axis of the drive pulley and in the plane of the latter while the tension pulley 44 is arranged to move transversely in any suitable manner and to turn about an axis above the axis of the pulley 42. A driving band or belt 45 encircles the spindles 40, 41, passing over the pulley 42 and about the pulley 43 and over the movable tension pulley 44. In this case also an integrally continuous driving band 45 may be employed.

While certain specific modifications and arrangements have been described as desirable, it is to be understood that these 50 are only by way of example and that the invention is capable of embodiment in other and equivalent mechanical devices.

I claim:

1. A machine of the class described comprising a pair of spaced spindles, a drive pulley intermediate said spindles, an endless band partially encircling said spindles, the entire band lying to one side of the axis of the drive pulley, a guide pulley arranged between one of said spindles and the drive pulley, a second guide pulley arranged between the other of said spindles and the drive pulley, a movable support for said second guide pulley, and means normally tending to move said second guide pulley in a direction to press a run of the endless band into contact with the drive pulley. 55 60 65

2. A machine of the class described comprising a pair of spaced spindles, an endless band engaging said spindles, a drive pulley intermediate said spindles, the axis of the pulley being outside of the band, a guide pulley mounted to turn about a fixed axis between one of the spindles and the 70 75 drive pulley, a second guide pulley arranged between the other spindle and the drive pulley, a movable support for said second guide pulley, and means constantly tending to move said support with its pulley toward 80 the drive pulley, each of the guide pulleys engaging said band and holding it in driving contact with the drive pulley. 85

3. A machine of the class described comprising two rows of spindles, a drive shaft therebetween having a drive pulley thereon, an endless integrally continuous band partially encircling a pair of spindles of each row and engaging the drive pulley, the oppositely moving runs of the band being disposed to one side of the drive shaft, a guide pulley mounted to turn about a fixed axis between the drive pulley and one row of spindles, a second guide pulley mounted upon one arm of a bell crank lever, the axis 90 95 of said pulley being between the drive pulley and the other row of spindles, and a weight upon the other arm of said bell crank lever constructed and arranged to press the movable guide pulley into contact with one run of the band. 100

Signed by me at Fales & Jenks Machine Co., Pawtucket, Rhode Island, this fourteenth day of February, 1923.

HERBERT G. BEEDE.
